UNITED STATES PATENT OFFICE.

HARRY SINGER, OF LOS ANGELES, CALIFORNIA.

IRRIGATING BOTTLE AND SYRINGE.

Application filed June 17, 1927. Serial No. 199,487.

My invention relates to medical apparatus and more particularly to a medicine container and syringe combined.

The primary object of my invention is to provide an irrigating bottle and syringe for holding liquid medicines or solutions and for ejecting a predetermined amount thereof from the container in the process of treating ailments or diseases requiring injections. 10 A further object is to provide a combined container and syringe of the character described which will occupy the space of an ordinary bottle, which is convenient to use and which easily may be kept in a sanitary condition. 15

Other objects and advantages will appear hereinafter and while I show herewith and will describe a preferred form of construction, I desire it to be understood that I do 20 not confine my invention to such preferred form but that various changes and adaptations may be made therein without departing from the spirit of my invention as hereinafter claimed.

25 Referring to the drawings which accompany this specification and form a part thereof,

Fig. 1 is a side view of a combined container and syringe, embodying the principles of my invention. 30

Fig. 2 is a sectional view of the container and syringe shown in Fig. 1, the section being taken in a vertical plane through the center thereof. 35

Fig. 3 is a transverse sectional view of the container and syringe, taken on line 3—3 of Fig. 1.

Fig. 4 is a side view of the plunger forming part of the syringe portion of my device. 40

Fig. 5 is a side view of my combined container and syringe with the removable part of the syringe unscrewed from the container, the latter being shown partly in section and partly in elevation, to illustrate its operation. 45

Fig. 6 is a view in perspective of the sanitary cap which is used to cover the syringe portion of my device, when not in use.

Fig. 7 is an enlarged sectional view of the cap shown in Fig. 6, the section being taken longitudinally thereof. 50

Fig. 8 is an enlarged transverse sectional

view of the inner part of the syringe barrel, the section being taken on line 8—8 of Fig. 5. 55

Fig. 9 is an enlarged view in perspective of the inner part of the syringe barrel by itself.

As indicated by reference numerals the apparatus consists, in detail, of a glass container 10, resembling an ordinary bottle, with a recessed bottom 11 having a central opening equipped with a soft rubber bushing 12. The bushing is provided with an annular groove adapted to receive the edge 13 of the opening, when compressed and inserted therein, whereby it is retained in place. The container is made with an externally screw-threaded neck 14, within which is sealed or otherwise fixed a tight-fitting glass tube 15, extending downwardly therefrom within the container. The lower end of tube 15 is closed except for a central opening 16; and a series of spaced apertures 17 are made through the wall thereof, somewhat above its closed end. 75

A screw-cap 18, adapted to screw onto neck 14 of container 10 is made of fibre, hard rubber or the like, and a second glass tube 19, exactly coinciding in thickness and diameter with tube 15 is fixed in cap 18 so that when said cap 18 is screwed onto neck 14 the lower end of outer tube 19 butts against the upper end of inner tube 15 and the two tubes combined to form a barrel or cylinder for the syringe portion of the device. The upper end of outer tube 19 is provided with a cone-shaped tip or nozzle 20 with a small central opening 21. 80

A glass plunger rod 22, of a diameter to 90 tightly fit in bushing 12 and a length somewhat less than the combined lengths of container 10 and outer tube 19, is inserted downwardly through opening 16 in tube 15 and bushing 12 before cap 18 and tube 19 are 95 screwed into place, said plunger rod having a terminal bead 23 on its upper end and a collar 24 in spaced relation thereto. A soft rubber disc 25, of a diameter to fit tightly within cylinder tubes 15 and 19 and a thickness equal to the space between bead 23 and collar 24, and having an axial opening approximately equal in diameter to that of plunger rod 22, is forced over bead 23 100

against collar 24 so that it is held between the former and the latter and serves as a plunger or piston in the cylinder formed by said tubes 15 and 19. A ball or bulb 26 is fixed on the projecting lower end of plunger rod 22, the size of said ball or bulb being such as to afford a convenient thumb-and-finger grasp and at the same time, when in its uppermost position to be flush with the bottom of the container so that it will rest firmly when placed on a plane surface. A red mark 27 and a blue mark 28 are made at spaced points on the plunger rod to indicate the position of the piston.

15 A glass or metal nozzle-cap 29, cylindrical in form and of a diameter to fit outer tube 19 loosely enough to be readily removable therefrom with a twist, is slipped over nozzle 20. The nozzle-cap is partially filled with 20 cotton 30, or other absorbent material, saturated with a suitable antiseptic liquid, so that it serves not only to prevent leakage from the container but also to disinfect the nozzle.

25 When the container is to be filled cap 18 is unscrewed and removed, together with outer tube 19, from the neck thereof and plunger rod 22 is actuated by means of bulb 26 to pull piston 25 below apertures 17 in 30 inner tube 15, as shown in Fig. 5. Red mark 27 appears just below bushings 12 to indicate that position. The liquid is poured into tube 15 and flows through apertures 17. When the container is properly filled cap 18 is screwed back onto its neck 14 and nozzle cap 29 is placed on nozzle 20 to prevent 35 leakage. The container is then inverted whereupon the liquid reenters apertures 17 filling the syringe barrel completely. The 40 plunger is now pushed inwardly until blue mark 30 is just visible outside of bushing 12. When thus adjusted piston 25 is in a position, as shown in dotted lines in Fig. 2, to close apertures 17 and prevent a backward 45 flow therethrough from the barrel into the container. The container is now turned upright and cap 19 is removed, whereupon the device is ready for use as a syringe, the barrel thereof containing a suitable amount of 50 the liquid for a dose. The liquid is ejected, as is evident, by pushing the plunger inwardly until bulb 26 comes in contact with bushing 12 and piston 25 is in the upper end of outer tube 19, as shown in full lines in 55 Fig. 2, in which position the piston serves

as a stopper. Nozzle-cap 29 is replaced after use so as to keep the nozzle sterilized.

Having thus illustrated and described my invention, I claim:

1. An irrigating bottle and syringe comprising a bottle shaped container; a bushing fixed in the bottom of said container to serve as a water-tight bearing; a syringe barrel fixed in the neck of said container, so as to extend partially inside and partially outside of said container, said barrel having apertures opening within said container; a plunger working in said barrel above and below said apertures, so as to admit liquid into said barrel and to eject it therefrom; and a plunger rod connected to said plunger so as to actuate it, said plunger rod extending through said bushing so as to be operable through the bottom of the container. 70

2. An irrigating bottle and syringe comprising a bottle shaped container; a bushing fixed in the bottom of said container to serve as a water-tight bearing; a syringe barrel fixed in the neck of said container; said syringe barrel being made in two abutting parts, an inner part fixed in the neck of the container and an outer part fixed in a screw-threaded cap adapted to screw onto the neck thereof, said inner part having apertures adjacent the lower end thereof opening into the container and said outer part terminating in a nozzle; a plunger working in said syringe barrel so as to admit liquid thereto, from said container, and to eject it therefrom through said nozzle, and a plunger rod connected to said plunger, said plunger rod extending through said bushing so as to be operable through the bottom of the container. 80

3. A combined container and syringe comprising a bottle-shaped vessel adapted to hold liquid, said vessel having a neck and a screw-threaded cap fitted thereon; a syringe barrel fixed in said neck and cap in two separable parts, an inner part extending within the vessel and an outer part removable with said cap; a plunger working in said syringe barrel so as to admit liquid thereto, from said vessel, and to eject a predetermined quantity of the liquid therefrom, and a plunger rod connected to said plunger so as to be operable through the bottom of the vessel. 95 100 105

HARRY SINGER.
